(57) **CLAIM**

The ornamental design for a “latch assembly for door lock”, as shown and described.

DESCRIPTION

FIG. 1 is a perspective view of a latch assembly for door lock showing my new design;
FIG. 2 is a top view thereof;
FIG. 3 is a bottom view thereof;
FIG. 4 is a front view thereof;
FIG. 5 is rear view thereof;
FIG. 6 is a left view thereof; and,
FIG. 7 is a right view thereof.
The broken lines illustrate unclaimed portions and form no part of the claimed design.
